CLAIM

The ornamental design for a security clip for joining a feed line to a cannula, as shown and described.

DESCRIPTION

FIG. 1 is a front, top and left side perspective view of a security clip for joining a feed line to a cannula, showing our new design; the broken line showing is for illustrative purposes only and forms no part of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof; and

FIG. 7 is a top plan view thereof.

FIG.1
